UNITED STATES PATENT OFFICE.

EDWARD A. HILL, OF CHICAGO, ILLINOIS, ASSIGNOR TO CHICAGO GRAIN DOOR COMPANY, OF CHICAGO, ILLINOIS, A CORPORATION OF ILLINOIS.

CAR-DOOR BRACKET.

No. 894,002.

Specification of Letters Patent.

Patented July 21, 1908.

Application filed March 14, 1908. Serial No. 421,207.

To all whom it may concern:

Be it known that I, EDWARD A. HILL, a citizen of the United States, residing at Chicago, in the county of Cook and State of Illinois, have invented certain new and useful Improvements in Car-Door Brackets, of which the following is a specification.

My invention relates to brackets for guiding and retaining the lower edges of freight 10 car doors, and particularly to brackets of the type known as safety brackets or burglar proof brackets, which are so constructed that they cannot be removed from the car when the door is closed without very great 15 difficulty and without so disfiguring the car that their removal will be immediately detected upon inspection.

The object of the present invention is to provide a new and improved construction of 20 car door bracket of the safety type which may be easily attached to the car by screws through bolts or even by barbed spikes, which shall be capable of use upon cars where it is not possible or convenient to use the ordinary 25 brackets now in use and which shall require but a small space for its attachment.

The invention is illustrated in the accompanying drawings wherein

Figure 1 is a side elevation of the central 30 portion of a freight car illustrating the door of the freight car guided and retained by the bracket of my invention. Fig. 2 is a vertical section through one of the brackets and the adjacent parts of the car. Fig. 3 is an 35 elevation of the same with the door removed and showing the bracket attached by the central attaching device and ready to receive the upper attaching screws or bolts. Fig. 4 is a plan view of the bracket; and Fig. 40 5 is a vertical section similar to that of Fig. 2 illustrating the attachment of the bracket to a car having a steel under-frame.

Like characters of reference indicate like 45 parts in the several figures of the drawings.

Referring to the drawings 1 represents the ordinary sliding freight car door which has the latch 2 adapted to be sealed in the customary manner.

3 represents the siding of the car, 4 one of 50 the door posts having the downwardly projecting part 5 which customarily extends over the front of the sill 6 but which I cut away so as to give a space for the attachment of the bracket.

55 7 represents the flooring of the car and 8

the usual filler which extends down over the sill and fills the space under the door between the two door posts. In order to make room for the attachment of my bracket in the manner to be hereafter described, this 60 siding is cut away on the diagonal as shown in Fig. 3.

The bracket consists of an arm having an upturned lip and an attaching plate 9 which latter is preferably substantially circular in 65 its configuration and provided with a central bolt or screw hole 10 to receive an attaching device which, in Figs. 2 and 3, is shown as an ordinary lag screw 11 provided with a squared head. The head may be, however, 70 of any shape even circular, although in such latter case the lag screw would have to be driven home by a sledge after the manner of a spike. I prefer, however, to use a lag screw with a polygonal head in order that it 75 may be driven down with a wrench. The plate 9 is provided with outstanding rib 12 around the bolt hole 10 and which preferably conforms to the shape of the screw head. When the screw has been driven home it will 80 be seen that this rib effectually prevents the bracket from being removed so long as the door stands above the bracket. The plate 9 is also preferably provided with the bolt 85 holes 13, 13, extending through bosses 14, 14, and which are not protected by ribs as is the central bolt hole. These holes receive the lag screws 15 or other equivalent attaching devices.

The bracket member or bracket proper, is 90 integral with the attaching plate and projects from the bottom thereof, comprising the horizontal ledge 16 and the upturned lip 17. The bracket member may be reinforced by the ribs 18, 18, 18, and by the curved re- 95 inforcing webs 19, 19.

When the bracket is to be attached in the ordinary way the central lag screw 11 will be driven down by a wrench or it may even be hammered down. The last few turns, however, will be given by engaging the ribs 12 with the screw head and turning the bracket bodily with the screw. If a through-bolt is used in place of the lag screw the nut on the bolt may be screwed up in the same manner. 105 It will be noticed that the protected bolt or screw hole of the bracket is located in the center of the bracket and that the bracket itself is substantially circular. Because of this the bracket may be attached in a space 110

which is just barely large enough to contain it when in place. This is important in certain sorts of freight cars now in use because it is not desirable to cut away any more of 5 the woodwork of the car than is necessary. It will be noted also that the attaching plate is entirely above the bracket arm. This allows the bracket to be used on cars in which the doors extend down to the bottom 10 of the sill while permitting the attachment of the bracket to the sill in the ordinary manner. This bracket may, of course, be used as well upon the older styles of cars in which the doors are shorter. The circular 15 construction of the bracket gives very great strength as well as compactness.

In freight cars in which the body of the car is supported upon a steel under-frame, it has 20 been customary to weld or otherwise secure the door brackets to the portion of the under-frame which supports the car sill. This was done very largely because in cars of this type the doors usually extend down to the bottom 25 of the sill. This method of attachment obviously has its disadvantages. It is a more or less difficult task to attach the iron bracket to the metal frame and if the bracket becomes broken there is considerable trouble and difficulty involved in removing the parts 30 and attaching a new bracket. The brackets of the present invention may be used on cars of this particular build. The bracket may also be attached by a through-bolt and will be just as securely attached as if a lag screw 35 were used because the head of the bolt will be concealed behind the steel under-frame. A bolt makes in some respects a better attachment than a lag screw because it extends clear through the sill and is not so likely to 40 become loose.

In Fig. 5 I have illustrated my bracket as attached to a car having a steel under-frame. The central or protected attachment is here shown as made by a through-bolt. In this 45 figure 20 represents a portion of the steel under-frame, 21 a steel bracket connected with the under-frame and which supports the car sill 6. 22 is a through-bolt having a countersunk head 23 and a nut 24 which will 50 be protected by the ribs 12 of the brackets.

It will be understood that the bracket of this invention is designed to be used on freight cars where the sliding door is to be sealed or otherwise secured in its closed position. If one or more of the brackets used to 55 guide and retain the lower edge of the door could, in such cases, be removed and replaced without detection it might be possible for a person wishing to rob the car to force 60 the bottom of the door out far enough to accomplish his purpose without breaking the seal or other fastening means used at the

front edge of the door. Cars provided with brackets which may be removed and replaced with but little disturbance may thus 65 be entered without breaking the seal.

I wish it to be understood that I do not desire to limit myself to the precise construction and arrangements above shown and described as modifications may be devised 70 which will come within the spirit of my invention.

I claim:

1. A car door bracket comprising a substantially circular attaching plate, a bracket 75 arm extending outwardly and upwardly from the lower edge of said plate, a hole in the center of the plate, and an attaching device to extend through said hole, said plate having a projecting rib around said hole and conformed to an engaging part of said attaching device, whereby the bracket, when being attached, may be rotated about its central point.

2. A car door bracket comprising a substantially circular plate having a hole in the center, a rib on the plate around said hole, a bracket arm extending from the lower edge of said circular plate and curved reinforcing webs reinforcing the connection between the 90 plate and the bracket arm, said attaching plate being provided with additional unprotected holes for attaching means.

3. The combination with the sill of a freight car and a door which reaches substantially to the bottom of the sill, of a door bracket for retaining and guiding the lower edge of the door, comprising a bracket arm extending at its outer end above the edge of the door, and having an attaching plate 100 adapted to be attached to the car sill and lying behind the door, said plate having a hole therethrough, a rib on the plate around said hole, and an attaching device which extends through the hole and into the car 105 sill and having a part which is protected by said rib.

4. The combination with the metal under-frame of a freight car and the sill and door of said car, of a metal support for said sill, and 110 a door bracket comprising an attaching plate lying against the front face of said sill, a bracket arm extending at its outer end above the lower edge of the door, a through-bolt with its head protected by said sill support 115 extending through the sill and through the attaching plate of the bracket, said attaching plate having a rib which surrounds and protects the nut of said bolt.

EDWARD A. HILL.
